CONTROL SYSTEM FOR ELECTRIC VALVES

Eduard Schorno, Zurich, Switzerland, assignor to
Maschinenfabrik Oerlikon, Zurich-Oerlikon,
Switzerland, a Swiss firm

Application February 10, 1947, Serial No. 727,612
In Switzerland February 12, 1946

10 Claims. (Cl. 315—261)

1

The present invention relates to a control system for electric valves and particularly to a grid extinguishing system to prevent arc-backs and overload currents.

Up to the present known devices or arrangements designed for the prevention of overload current or arc-backs in electric valves do not prevent the formation of an arc-back but are merely concerned in putting out or extinguishing such an arc after its formation, using for this purpose grid action which is initiated only after the occurrence of this phenomenon called arc-back. This grid action is usually designed to respond to currents and voltages supplied by the alternating current or direct current network of the rectifier. Whenever an arc-back occurs the rectifier, the rectifier-transformer and the associated equipment is subjected to heavy overload stresses and the so stricken elements suffer often serious damages.

The main purpose of the present invention is therefore to provide a suitable system to prevent the arc-back phenomenon by extinguishing the normal arc or blocking of the anodes by grid action before the arc-back phenomenon takes place. The coordination of the necessary elements to achieve this is referred to as grid extinguishing system and according to this invention said grid extinguishing system actuated by fractional voltages of the normal arc voltage. In this respect it has been established that the voltage fluctuations of said arc furnishes a criterium for the arc-back phenomenon and that its occurrence is invariably due to excess voltage of certain magnitude of the normal arc.

Other features will be apparent from the detailed description of a control system, incident to the present invention, described hereafter in conjunction with the accompanying drawing in which is:

Figure 1 a control system for a mercury arc rectifier in which the arc voltage between the vessel and the cathode is used to actuate the grid extinguishing system of the faulty working anode, in order to prevent arc-back.

Figure 2 shows the application of a glow tube in a system according Figure 1.

Figure 3 shows the application of gas type discharge tubes, incidental to the behavior of the normal arc, characterized by the occurrence of excess voltages before a back-arc is initiated, as noted above.

Referring to Figure 1—showing diagrammatically a system of few inexpensive elements—1 indicates the rectifier-transformer, 2 the rectifier

2

vessel, 3 the anodes, 4 the grids, 5 an anode housing, 6 the cathode, 7 the arc, 8 the grid-resistors, 9 a quick acting relay, 10 an auxiliary rectifier, 11 a relay, 12 a battery, 13 alternating current net work terminals of approximately 220 volts and 14 a switch; 15 indicates the holding coil of the quick acting relay 9.

In a rectifier working at full load arc-backs are apt to develop, when changes in the degree 10 of vacuum, respectively changes in the pressure of the mercury vapor occur or in cases of heavily increased load current. Under such conditions the arc voltage increases, to such a value in the 15 circuit arrangement shown that the quick acting relay 9, controlled by the voltage drop between the vessel and cathode, is actuated, thereby connecting all grids 4 with the negative terminal of the battery 12, blocking thereby the rectifier operation before arc-backs can occur. The potential between the vessel and cathode is a measure 20 of the normal arc voltage. It is also apparent that it is possible to select an operating coil for the quick acting relay 9 which will be operable on an overload current of the rectifier. In order 25 to prevent relay 9 to return immediately to its operating position after its blocking operation, the armature of relay 9 is caused to remain attracted by means of the holding coil 15, which is fed from the rectifier 10. At the instant the 30 relay 9 functions the rectifier 10 is supplied with A. C. current, in that the armature of relay 11 falls off and connects two contacts, thereby closing the supply circuit of the rectifier 10. By 35 opening and reclosing the switch 14 in the output circuit of the rectifier 10 the grid blocking action of the relay 9 can be made inoperative. When the circuit of the holding coil 15 is interrupted and the quick acting relay 9 is reset by means of a spring, the entire rectifier system resumes 40 its normal operating position and the control system is again ready to protect the rectifier against the back-arc phenomenon.

In the modified system according Figure 2 the quick acting relay 9 is connected to an auxiliary electrode 27, provided for each anode 3, over the intermediary of a glow tube 16. Thus the voltage between the auxiliary electrode and the cathode is employed as a measure for the arc voltage. The glow tube 16 is rated to respond to a 45 voltage adapted to the type of rectifier to be protected, operating the quick acting relay 9 whenever it is necessary to protect the rectifier against the "back-arc" phenomenon initiated by over voltage or overload current.

It will be apparent that other fractional volt-

ages of the normal arc voltage such as grid-cathode, grid-vessel, grid to grid and anode to grid may also be used to actuate the grid extinguishing system. In the system according to Figure 2 vacuum tubes may be used replacing the glow tube or for direct feeding of the holding coil 15 of the quick acting relay 9. Damaged parts of the rectifier or unclean vessels may promote back-arcs.

In a properly built rectifier or valve when working under normal condition at its rated load, back-arc occurs only seldom. However under overload especially when said overload is maintained over a long period of time, back-arcs are apt to become a common occurrence.

Tests and careful watching of the behavior during operation have shown that back-arcs always occur during the time of zero current passage and particularly immediately after the interruption of the normal arc. It appears to be characteristic for this behavior that shortly before arc-backs, toward the end of the current pulse, the normal arc voltage between anode and cathode increases to a magnitude equal to several times the value of the normal arc voltage. The modifications of the system shown in Figure 3 therefore comprises means whereby only the faulty operating anode is extinguished by its associated grid extinguishing system. By this, normal operation of the rectifier, while the protective device is actuated, is not interrupted.

Referring to Figure 3, the numerals 17, 18 and 19 indicate resistors, 20 are time delay relays, 21 are signalling relays and 22 are gas type discharge tubes; 23 indicate means to provide for grid control voltage. Assuming that the rectifier operates under overload and that at one of the anodes abnormal high peak voltages towards the end of a current pulse occur, then the modified system operates as described hereafter. The arrangement comprises an auxiliary electrode 4' designed to serve as voltage tap which is connected with the grid of the gas type tube 22 over an intermediate limiting resistor 19. The tube 22 under the assumed condition will begin to glow closing thereby the circuit over said tube 22, grid battery 12 and resistors 17 energizing the upper grid 4, in relation to the cathode 6, by a negative potential, whereby the particular anode 3 is blocked. Operation of the other anodes of the rectifier is thereby not interrupted and merely a slight drop in the output voltage will be noticed. The time relay 20 is designed to put the particular anode 3 after a predetermined time back in operation again, thereby compensating said previous voltage loss. The normal operation of the rectifier is hardly affected while the protective equipment of the modified system functions to prevent the back-arc phenomenon. It is understood that hand operated means may also be used to block the faulty anode. The signalling relay 21 operating electromagnetically or by photoelectric cells, in well known manner, is designed to indicate the faulty operating anode.

In cases where the signalling of the faulty anode or uninterrupted operation—in view of only short interruptions—is of no necessity the system may be further modified in that but one tube 22 is employed.

In another modification of the grid extinguishing system some greater part of the arc voltage such as the voltage between an auxiliary electrode to cathode or grid to cathode may be used to actuate the grid extinguishing system.

What I claim is:

1. In combination with an electric valve means comprising at least one anode, a cathode and a control grid, means forming a grid extinguishing system and including a relay, circuit means for directly energizing said relay by a fraction of the arc voltage, a normally open circuit containing a source of direct current having its positive terminal connected with said cathode, and means operated by said relay when said fraction of said arc voltage exceeds a predetermined value to conductively connect said control grid with the negative terminal of said direct current circuit, whereby said grid extinguishing system becomes operative to block the anode associated with said grid.

2. In combination with an electric valve means comprising at least one anode, a cathode and a control grid, means forming a grid extinguishing system and including a relay, circuit means for directly energizing said relay by a fraction of the voltage drop between said anode and said cathode, a normally open circuit containing a source of direct current having its positive terminal connected with said cathode, and means operated by said relay when said fraction of said voltage drop exceeds a predetermined value to conductively connect said control grid with the negative terminal of said direct current circuit, whereby said grid extinguishing system becomes operative to block the anode associated with said grid.

3. In combination with an electric valve means comprising at least one anode, a cathode, a control grid and an auxiliary electrode arranged in a vessel, means forming a grid extinguishing system and including a relay having a normally deenergized holding coil, circuit means for directly energizing said relay by the voltage drop between said auxiliary electrode and said cathode, a normally open circuit containing a source of direct current having its positive terminal connected with said cathode, and means operated by said relay when said voltage drop exceeds a predetermined value to conductively connect said control grid with the negative terminal of said direct current circuit and to cause energization of said holding coil, whereby said grid extinguishing system becomes operative to block the anode associated with said grid and manually operable means to cause deenergization of said holding coil and a disconnection of said control grid from said negative terminal.

4. In combination with an electric valve means comprising at least one anode, a cathode, a control grid and an auxiliary electrode arranged in a vessel, means forming a grid extinguishing system and including a relay, circuit means including a glow tube for directly energizing said relay by the voltage drop between said auxiliary electrode and said cathode, a normally open circuit containing a source of direct current having its positive terminal connected with said cathode, and means operated by said relay when said voltage drop exceeds a predetermined value to conductively connect said control grid with the negative terminal of said direct current circuit, whereby said grid extinguishing system becomes operative to block the anode associated with said grid.

5. In combination with an electric valve means comprising at least one anode, a cathode and a control grid arranged in a vessel, means forming a grid extinguishing system and including a relay having a movable armature and a nor-

mainly deenergized holding coil, circuit means for directly energizing said relay by the voltage drop between said vessel and said cathode, a normally open circuit containing a source of direct current having its positive terminal connected with said cathode, and means operated by the movable armature of said relay when said voltage drop exceeds a predetermined value to conductively connect said control grid with the negative terminal of said direct current circuit and to cause energization of said holding coil, whereby said grid extinguishing system becomes operative to block the anode associated with said grid and manually operable means to cause deenergization of said holding coil and a disconnection of said control grid from said negative terminal.

6. In combination with an electric valve means comprising at least one anode, a cathode, a control grid and an auxiliary electrode arranged in a vessel, means forming a grid extinguishing system and including a relay, circuit means including a gas discharge valve for energizing said relay by the voltage drop between said auxiliary electrode and said cathode, a normally open circuit containing a source of direct current having its positive terminal connected with said cathode, and means operated by said relay when said voltage drop exceeds a predetermined value to conductively connect said control grid with the negative terminal of said direct current circuit, whereby said grid extinguishing system becomes operative to block the anode associated with said grid.

7. In combination with an electric valve means comprising at least one anode, a cathode, a control grid and an auxiliary electrode arranged in a vessel, means forming a grid extinguishing system and including a relay, circuit means including a signalling relay for energizing said relay by the voltage drop between said auxiliary electrode and said cathode, a normally open circuit containing a source of direct current having its positive terminal connected with said cathode, and means operated by said relay when said voltage drop exceeds a predetermined value to conductively connect said control grid with the negative terminal of said direct current circuit, whereby said grid extinguishing system becomes operative to block the anode associated with said grid.

8. In combination with an electric valve means comprising at least one anode, a cathode, a control grid and an auxiliary electrode arranged in a vessel, means forming a grid extinguishing system and including a relay, circuit means including a gas discharge valve and a signalling relay for energizing said relay by the voltage drop between said auxiliary electrode and said cathode, a normally open circuit containing a source of direct current having its positive terminal connected with said cathode, and means operated by said relay when said voltage drop exceeds a predetermined value to conductively

connect said control grid with the negative terminal of said direct current circuit, whereby said grid extinguishing system becomes operative to block the anode associated with said grid.

9. In combination with an electric valve means comprising a plurality of anodes, a cathode, a control grid for each anode and an auxiliary electrode for each anode, means forming a grid extinguishing system and including a plurality of relays, one for each anode, circuit means for each said relays for energizing said relays by the voltage drop between the auxiliary electrode of their associated anode and said cathode, a normally open circuit containing a source of direct current having its positive terminal connected with said cathode, and means operated by each of said relays when the voltage supplied to the same exceeds a predetermined value to conductively connect the control grid associated with the respective auxiliary electrode with the negative terminal of said source of direct current, whereby the grid extinguishing system becomes operative to block solely the anode associated with said control grid, the other anodes remaining in operative condition.

10. In combination with an electric valve means comprising at least one anode, a cathode and a control grid, means forming a grid extinguishing system and including a relay, circuit means for energizing said relay by a fraction of the arc voltage, a normally open circuit containing a source of direct current having its positive terminal connected with said cathode, means operated by said relay when said fraction of said arc voltage exceeds a predetermined value to conductively connect said control grid with the negative terminal of said direct current circuit, whereby said grid extinguishing system becomes operative to block the anode associated with said grid, a holding coil operatively connected with said relay, a second circuit means adapted to be automatically closed when said relay is rendered operative to energize said holding coil and thereby holding said relay in its grid extinguishing position, and manually operable switch means in said second circuit means for opening the latter and causing deenergization of said holding coil.
